UNITED STATES PATENT OFFICE.

FRED T. HIGGINS, OF KLAMATH FALLS, OREGON.

LAMP-BURNER ATTACHMENT.

1,112,451.

Specification of Letters Patent.

Patented Oct. 6, 1914.

Application filed February 21, 1914. Serial No. 820,267.

To all whom it may concern:

Be it known that I, FRED T. HIGGINS, citizen of the United States, residing at Klamath Falls, in the county of Klamath and State of Oregon, have invented certain new and useful Improvements in Lamp-Burner Attachments, of which the following is a specification, reference being had to the accompanying drawings.

10 This invention relates to certain improvements in lamp burners and more particularly to a burner attachment which has for its primary object to provide means whereby air is freely supplied to the burner tip so that a maximum flame may be obtained from a minimum consumption of fuel, said attachment also being provided with means for supporting the lamp chimney whereby liability of breaking of the chimney by the 15 intense heat will be obviated.

In its more specific aspect, the invention embodies a sectional cap adapted to be mounted upon the body of the burner, said cap being provided with means for admitting air to the space between the same and the burner tip and also between the exterior of the cap sections and the lamp chimney.

The invention has for a further object to produce a burner attachment of the above character which is extremely strong and durable in its construction, may be inexpensively manufactured and is highly serviceable and convenient in practical use.

With the above and other objects in view as will become apparent as the description proceeds, the invention consists in certain constructions, combinations and arrangements of the parts that I shall hereinafter fully describe and claim.

40 For a full understanding of the invention, reference is to be had to the following description and accompanying drawing, in which—

Figure 1 is a vertical section through the lower portion of a lamp chimney showing my improved attachment applied to the burner and the chimney supported thereon; Fig. 2 is a side elevation of the attachment, the sections thereof being separated; Fig. 3 is a section taken on the line 3—3 of Fig. 1; Fig. 4 is a detail section through the engaged edges of adjacent cap sections.

Referring in detail to the drawing, 5 designates the burner proper which is provided with a base flange 6 and a threaded cylindrical portion 7 which is adapted for

engagement in a correspondingly threaded opening provided in the oil cup or reservoir. To the base flange 6 of the burner, the usual upwardly extending spring arms 8 are secured for clamping engagement against the lower end of a chimney indicated at 9.

My improved attachment includes a plurality of similarly constructed sections 10 which are molded or otherwise formed of refractory or heat resisting material of any desired character. Each of these cap sections 10 is of concavo-convex form in cross section and is provided upon its outer convex face intermediate of its ends with a laterally projecting enlargement 11, having the outwardly and upwardly inclined peripheral face 12, the purpose of which will be later explained.

Upon the lower edge of each of the cap sections 10, a laterally projecting flange 13 is formed, and this flange is provided with radially disposed ribs indicated at 14 which produce in the bottom face of said flange, 80 the grooves 15. Each of the cap sections is further provided between the enlargement 11 and the flange 13 and upon its end edge with a flange 16, while the opposite edge of said cap section is rabbeted or recessed 85 as at 17. The sections 10 when properly assembled upon the burner are arranged with the flange 16 of one section engaged in the groove 17 in the abutting edge of an adjacent section of the cap. Between these 90 overlapping edge portions of the cap sections and the apex of the cap, each section is reduced in width whereby the slot 18 is formed, to accommodate the wick of the burner.

When the cap sections are arranged upon the burner flange 6 as shown in Fig. 1 of the drawings, air may enter between the flanges 13 on the cap sections and the burner flange 6 to the space between said cap and the burner, so that proper combustion of the fuel at the burner tip is assured and a maximum flame thereby produced. Air will also enter between the lower edge of the chimney and the flanges 13, said chimney being disposed upon the radial ribs 14. This cold air striking upon the outer peripheral faces of the cap sections 10 is directed by the inclined walls 12 thereof outwardly against the wall of the chimney 9. Thus liability 105 of breaking or cracking the chimney by the intense heat of the flame from the burner

will be overcome. By constructing the burner cap in sections as above explained, said sections may move relative to each other by expansion thereof and breakage of the cap thereby is prevented. It will thus be apparent that by means of my improved burner attachment, considerable economy may be effected in the use of oil or gas burning lamps.

10 From the foregoing description taken in connection with the accompanying drawing, it is believed that the construction, manner of operation and several advantages of my invention will be clearly and fully 15 understood.

The attachment is extremely simple in its construction, highly reliable and efficient in practical use and obviates serious deficiencies in such devices as heretofore constructed. It will of course be apparent that my burner cap may be produced in any desired number of sections, and also in other forms than that illustrated in the drawing. The invention is also susceptible of a great 25 many other modifications in the form, proportion and arrangement of the several elements and I therefore reserve the privilege of resorting to all such legitimate changes as may be fairly embodied within the spirit 30 and scope of the invention as claimed.

Having thus described the invention, what is claimed is:

1. The combination with a burner provided with a body flange, of a cap therefor 35 consisting of a plurality of sections each provided with a flange adapted to be seated upon said burner flange, and having a plurality of grooves in its bottom face through which air is admitted into the space between 40 the burner and the cap, each of said cap sections being also provided with means to support a lamp chimney in spaced relation to the flanges thereon.

2. The combination with a burner provided with a body flange, of a cap therefor, 45 comprising a plurality of similar sections adapted for arrangement upon said burner flange, the adjacent sections having overlapping edge portions and spaced edge portions to accommodate the burner wick, each 50 of said cap sections being further provided in its lower edge with a radial groove

whereby air is admitted to the space between the cap and the burner, and additional means formed on said cap sections to support a lamp chimney upon the same and to provide air inlet openings between the lower edge of the chimney and the cap sections whereby air is admitted to the lower end of the chimney exteriorly of the cap.

3. The combination with a burner provided with a body flange, of a cap therefor comprising a plurality of similar sections adapted for arrangement upon said burner flange, the adjacent sections having overlapping edge portions and spaced edge portions to accommodate the burner wick, each of said cap sections being further provided in its lower edge with a radial groove whereby air is admitted to the space between the cap and the burner, and additional means formed on said cap sections to support a lamp chimney upon the same and to provide air inlet openings between the lower edge of the chimney and the cap sections whereby air is admitted to the lower end of the chimney exteriorly of the cap, each of said cap sections being further provided with means for directing the air outwardly against the chimney wall.

4. The combination with a burner provided with a body flange, of a cap therefor consisting of a plurality of sections each having a flange formed on its lower edge for engagement upon said burner flange, a plurality of radial ribs formed upon each of said cap flanges and producing grooves in the bottom face thereof through which air may enter to the space between the cap and the burner, said ribs being adapted to support a lamp chimney in spaced relation to the flanges on the cap sections through which air may enter to the space between the cap and the chimney, and an enlargement formed upon each of said cap sections 95 having an outwardly inclined face to direct the incoming air outwardly against the wall of the lamp chimney.

In testimony whereof I hereunto affix my signature in the presence of two witnesses.

FRED T. HIGGINS.
